UNITED STATES PATENT OFFICE.

JOSEPH W. SHARP, JR., OF BERWYN, PENNSYLVANIA, ASSIGNOR TO HAINES, JONES & CADBURY INCORPORATED, A CORPORATION OF PENNSYLVANIA.

FAUCET CONTROL.

1,345,643.

Specification of Letters Patent.

Patented July 6, 1920.

Application filed March 16, 1917. Serial No. 155,157.

To all whom it may concern:

Be it known that I, JOSEPH W. SHARP, Jr., a citizen of the United States, residing at Berwyn, in the county of Chester, State of Pennsylvania, have invented a new and useful Faucet Control, of which the following is a specification.

My invention relates to improvements in faucet control and comprises means for controlling or reducing or interrupting the flow through the faucet, which is additional or supplemental to the usual main or hand-controlled valve. The invention also comprises improvements in details of construction.

Referring to the drawings, which illustrate merely by way of example, suitable means for the embodiment of my invention:

20 Figure 1 is a side elevation.

Fig. 2 is a longitudinal vertical section.

Fig. 3 is a detail in perspective of the supplemental valve element.

25 Fig. 4 is a similar view of the washer operating therewith.

Fig. 5 is a similar view of the cap nut.

Similar numerals refer to similar parts throughout the several views.

In the example shown in the drawing, 30 my improvement is applied to what is known as a quick faucet, or a quick acting faucet, in that the main valve 7, which is carried by the nozzle element 8, having threaded connection with the body or fixed portion 9, is brought to seat, or into closed relationship with the valve seat 11, by a partial rotative movement of nozzle member 8, by means of the handle 12.

The body portion 9, which is connected to 40 the neck portion 13, leading to the supply pipe, is provided from the upper end thereof to a point below the aperture or bore 14 of the neck, with a bore of greater diameter than the bore of said body portion 9 below said point, whereby the shoulder 15 is provided between said differing diameters. Within this portion of larger bore is inserted the hollow cylinder member 16, open 45 at the bottom and provided with the port or opening 17, which is adapted to register with the bore 14 of the neck portion.

The upper end of the cylinder 16 is closed and is provided with a lug or plug 18 preferably projecting above the surrounding 50 wall of the cylinder, and is provided at its

top with a slot similar to the slot in a screw head, or it may be provided with other suitable means for manipulation, preferably by means of a tool.

The upper outer margin of body portion 9 60 is threaded to receive the interior thread of the cap-nut 19, which is adapted to surround the lug 18, of cylinder 16, and to exert pressure upon the washer 20 interposed between the top of the cylinder and said cap nut 19. 65

It will be understood that the cylinder is constructed to have a substantially watertight movable fit in the body portion 9, so that it may be turned by a suitable instrument, such as a screw driver, to bring the 70 aperture 17 into, or out of register with the bore 14 of the neck portion.

This device may be utilized for the accomplishment of either of two purposes;

Where for example, it is desired to remove the valve 7 for repairs, the valve cylinder 16 is turned so that opening 17 will not register with bore 14, which will result in shutting off the water entirely above the nozzle.

Where it is desired to reduce the force or volume of flow of water through the nozzle, because of abnormally high pressure or other cause, the cylinder 16 is adjusted so as to secure only a partial register between 85 port 17 and bore 14. With valve 7 entirely open this cylinder 16 may be adjusted until the desired flow through nozzle 8 is secured. When the proper adjustment is secured, the cap-nut is screwed down tightly on the 90 washer 20, so that all leak is prevented through the top of the body portion 9, and at the same time the valve cylinder is locked in such position of adjustment. The member 8 is provided with a number of projections or parallel ribs having shoulders 21. These ribs form recesses between them for receiving the set-screw 22 for securing the operating member or handle 12 in proper position of adjustment with respect to member 8. This member 12 is provided with an opening for receiving member 8 and is also provided with a flange 23 for engaging the shoulders 21 of the projections which prevents the accidental disengagement of member 12 from member 8 in case the set-screw becomes loosened.

110

What I claim is:

In a faucet, the combination of a tubular neck portion and a vertically extending cy

cylindrical portion or housing integral therewith, said housing portion having an enlarged bore in its upper extension and a valve seat near its lower end, a cylindrical 5 valve member seated in said enlarged bore, open at the bottom and closed at the top and provided with a port adapted to register with the bore of the neck portion, a nozzle member threaded on the lower end of the 10 housing and provided with peripheral pro-

jections, a valve member mounted within the nozzle member, and a nozzle-actuating member having a portion surrounding the nozzle member and provided with an inwardly extending peripheral flange for engaging said projections, said actuating member also provided with means for engaging the nozzle member between adjacent projections. 15

JOSEPH W. SHARP, JR.
